UNITED STATES PATENT OFFICE.

ISAAC E. PALMER, OF MIDDLETOWN, CONNECTICUT.

DESIGN FOR A HAMMOCK.

SPECIFICATION forming part of Design No. 19,110, dated May 21, 1889.

Application filed November 6, 1888. Serial No. 290,167. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification.

I will describe in detail a design for hammocks embodying my invention, and then point out the novel features in the claim.

The accompanying drawing is a perspective view of a hammock embodying my design.

The design consists, essentially, of a hammock-body in which the body portion A thereof is curved longitudinally or in the direction of its length, while the portions B thereof will have the appearance of being draped from the portion A, and will be longitudinally curved or curved in the direction of their lengths. The portions B also present

the appearance of being tapered, and are wavy in parts. I have shown stripes *a* delineated upon the portions A B of the hammock, which extend approximately parallel to each other ²⁵ and in the same direction; but these may be omitted. Below the portions B of the hammock are fringe-like portions C.

I have not described any of the means shown whereby the hammock-body may be suspended, because the same does not form a part of my design, broadly considered.

What I claim as my design is—

The design for a hammock, consisting of the longitudinally-curved portion A and the ³⁵ longitudinally-curved drapery-like portions D, having a wave-like appearance, substantially as shown and described.

ISAAC E. PALMER.
